COMBINED SEAMING AND PINKING MECHANISM

Geoffrey Stevenson, Brookline, Mass., assignor to
 Lewis Invisible Stitch Machine Company,
 St. Louis, Mo., a corporation of Maine

Application October 3, 1940, Serial No. 359,515

6 Claims. (Cl. 112—123)

The invention herein disclosed relates to a combined seaming and pinking mechanism for effecting the conjoint seaming and pinking of the material operated upon.

An object of the invention herein disclosed is to provide a machine of this kind with which various seaming and pinking operations may be performed. Another object of this invention is to provide a machine of this kind in which the pinking mechanism may be rendered ineffective and the machine utilized as a plain stitcher. A further object of the invention is to provide in a machine of this kind a positive drive for the pinking mechanism.

The foregoing objects and certain advantages that will hereinafter appear are realized in accordance with the invention in the machine illustrated in the drawings and which constitutes one specific example of embodiments of the invention. This machine is described below with references to the drawings. The drawings include:

Fig. 1 which is a side elevation of a combined seaming and pinking mechanism, partly broken away;

Fig. 2 which is a bottom plan of the same;

Fig. 3 which is a section taken on the line 3—3 of Fig. 1;

Fig. 4 which is a section taken on the line 4—4 of Fig. 1; and

Fig. 5 which is a partial plan of the bed of the machine.

The machine illustrated in the drawings comprises an ordinary sewing machine of the kind known as a plain stitcher and may be the well-known "Singer" Class 95—80 machine or a machine of the kind illustrated in the Stevenson Patent No. 2,165,312. This machine includes a base 1 that has two depending feet 2 adjacent one end and a substantially central foot 3 adjacent the other or needle end. The central depending foot or lug 3 is provided with an extension 4 which, in the particular machine illustrated, is the head of a machine screw that is threaded into the bottom of the lug. Upon these three lugs, the machine rests when it is not mounted in a table. Extending upwardly from the base, there is the usual standard 5 from which extends an arm 6 that carries at the end thereof a stitching head 7. The arm 6 is shown broken away to illustrate the main shaft 8 which extends through the arm 6, is journaled therein and extends through the standard 5. On the end of this

shaft, extending from the standard 5, the usual hand wheel and pulley 9 is secured.

The needle 10 of the stitching head cooperates with the usual rotary loop taker 11 for forming a lock stitch. The loop taker is mounted on the end of a shaft 12 that is journaled in the lug 3 and which extends to the standard end of the machine to be connected, in the usual manner, to the main shaft 8 of the machine by a shaft extending through the standard 5. In this manner, the hook 11 is operated in timed relation with respect to the reciprocations of the needle 10. The machine is necessarily provided with the usual throat plate 13 having the needle opening 14, the usual feed dogs 15 for feeding the cloth past the needle and the operating mechanism therefor.

The pinking mechanism is applied to the sewing machine and is arranged to be driven from the main shaft of the machine through a positive drive connection. This pinking mechanism includes a female knife 16, that is flush with the bed of the machine and the needle plate, and that has an opening therethrough. The opening 20 in the female knife includes a rectangular portion 16a and a V-shaped portion 17. The edges of the V-shaped portion of the opening form converging cutting edges which cooperate with cutting edges on a male knife 18, having an overhanging section 19 of a shape comparable to the opening through the female knife, to effect a V-shaped cut in the material operated upon. The male knife is mounted to be reciprocated in the female knife and the overhanging V-shaped portion 19 thereof cooperates with the edges of the female knife to effect a V-shaped cut upon downward movement of the male knife or movement in a direction to withdraw from the female knife.

The male knife includes a rectangular portion 20 that is secured to the upper end of a knife carrier 21 by a machine screw 22. The knife carrier 21 is curved as indicated in Fig. 4 so that the upper end of the knife carrier is approximately in line with the needle and the lower end 45 of the carrier is to one side of the hook shaft 12. The curvature of the knife carrier 21 is such as to provide room for the set screws by which the hook 11 is secured on the end of the hook shaft 12. The knife carrier is pivotally mounted between its ends upon a shaft 23 that extends from and is secured to the adjacent end of a lever 24. A collar 25 is provided and secured to the shaft 23 to prevent sideward movement of the knife carrier on the shaft. The lever 24 is pivotally mounted between its ends upon a shaft 26

that is secured in and extends from a depending lug or arm 27 formed on a bracket 28 that is secured to the bed of the machine on the underside thereof. This bracket lies along the under surface of the bed of the machine and it is secured to the bed by machine screws 28a extending through slots 28b. With this arrangement the bracket may be moved toward and away from the needle and so adjustably positioned with respect to the needle. The end 28c of the bracket constitutes an overhanging extension at the portion of the base adjacent the needle which is of lesser thickness.

The lever 24 is actuated about its pivotal mounting on the shaft 26 to effect reciprocatory movement of the male knife in the female knife. The angle of the cutting edges of the male knife is slightly less than the angle of the cutting edges of the female knife and the cutting edges of the male knife are resiliently urged into cutting relation with the cutting edges of the female knife by a spring 29. This spring is connected at one end to a machine screw 30 secured in the lower end of the knife carrier 21, that is, the end of the knife carrier on the side of its pivotal axis opposite to the side which carries the male knife. The other end of the spring 29 is secured in an eye 31 having a threaded shank that extends through a lug 32 formed on and extending from the lever 24. On the end of the shank extending through the lug there is a nut 33 which abuts against the lug 32 and prevents the eye from pulling through the lug. By adjusting the nut 33, the force of the spring may be increased or lessened.

It will be seen that this spring 29 tends to cause the knife carrier 21 to move about its pivotal axis in a direction to move the apex of the male knife towards the apex of the female knife. Such movement is resisted by the engagement of the edges of the male knife with the edges of the female knife. When the male knife extends through the female knife, the rectangular portion of the male knife engaging in the rectangular section of the opening through the female knife prevents the male knife from moving forward under the action of the spring. As the male knife enters the female knife and moves in a direction to be withdrawn therefrom, the converging edges of the male knife move along the converging edges of the female knife. When it is desired to remove the male knife either for sharpening or to replace it, it is desirable that the force of the spring 29 be rendered ineffective. To this end, a stop screw 34 is provided. This stop screw extends through and is threaded in the lever knife carrier 21. It is provided with a finger piece 35 through which it may be turned. The end of the stop screw 34 is positioned to engage a lug 36 formed on the lever 24. When the stop screw is turned to effect engagement with the lug 36, the spring is rendered ineffective and the knives can be readily removed and replaced.

Actuation of the lever 24 to effect reciprocatory movement of the male knife is effected through a connection to the end of the lever opposite to that to which the knife carrier 21 is connected. This connection is in the first instance to the end of a lever 37 that is also pivotally mounted on the shaft 26 beside the lever 24. The levers 24 and 37 are connected together through a toggle that consists of a link 38 pivotally secured at one end to the lever 37 and a link 39 to one end of which the other end of the link 38 is pivotally secured.

The opposite end of the link 39 is pivotally secured to the end of the lever 24.

This toggle may be broken to render ineffective the drive connection between the levers 24 and 37. The pivot by which the two links 38 and 39 are secured together is provided with a head 40 having a ball socket therein which receives the ball 41 of a fitting 42. The fitting 42 is bored transversely and receives a rod 43 that is provided with collars 44 and 45, one on each side of the fitting 42. The rod is connected at its other end to a fitting 46 having a ball 47 that is received in a ball socket 48 secured on a crank 49. The crank 49 is secured to a shaft 50 that extends through the base of the machine and has secured thereon a lever 51. By means of the lever, through the crank 49, the rod 43 and the collars 44 and 45, the pivot 40 may be shifted so as to break the toggle. In Fig. 1, the toggle is shown in the operative position, just over dead center, to the right as seen in Fig. 1, and against a pin 55. It is held in this position by a spring 52 that extends between the levers 37 and 24. When the lever 51 is moved away from the standard 5, the collar 45 engages the fitting 42 and breaks the toggle, the spring 52 causing the lever 24 to move about its pivot when the toggle is broken. On opposite movement of the lever 51, the collar 44 engages the pivot and makes the toggle; carrying the levers to the position shown in Fig. 1, slightly over dead center and against the pin 55.

The lever 37 is actuated in timed relation with the needle through a positive track cam 56 that is mounted upon a shaft 57 journaled in a bearing bracket 58 secured to the under side of the arm 6 of the sewing machine. At this point the arm is milled to receive a gear 59 that is also secured on the shaft 57 and to the track cam 56. The gear 59 meshes with a gear 60 secured on the main shaft 8 of the sewing machine. In this way, the track cam 56 is rotated in accordance with the main shaft 8 of the sewing machine. A cam follower 61 mounted on the lever 62, intermediate the ends of the lever 62, extends into the track of the cam 56. One end of the lever 62 is pivotally mounted at 63 between the bifurcated arm of a bracket 64 that is secured on a standard 65 extending from and secured in the bed 1 of the machine. The other end of the lever 62 is connected by a flexible link 66 to one end of a connecting rod 67 that extends through and is slidable in the standard 65. The connecting rod extends through the base of the machine and a bracket 68 is secured on the lower end thereof. A flexible link 69 connects the bracket 68 to the lever 37.

It will thus be seen that when the main shaft is rotated, the track cam is also rotated through the gear 59. The cam is rotated once for every two rotations of the main shaft, that is, the cam rotates once for each two reciprocations of the needle. The cam is designed to move the male knife in and out of the female knife, on alternate strokes of the needle, while the needle penetrates the goods and during the time when the feed dogs are stationary. It will be seen that as the cam follower is moved up and down by the track cam, the connecting rod 67 is moved up and down in the standard 65. This causes an oscillation of the lever 37 which is transmitted, during the operation of the pinking mechanism, through the toggle to the lever 24.

If it be desired to render the pinking mechanism inoperative, the lever 51 is moved so that

the collar 45 engages the fitting 42 and breaks the toggle. When this occurs, the male knife is pulled downwardly into the female knife, so that the top of the male knife is below the top of the female knife, by the spring 52 and the oscillations of the lever 37 are taken up by oscillation of the toggle link 33. The male knife thus remains stationary when the toggle is broken. To render the pinking mechanism again operative it is only necessary to move the lever 51 so that the collar 44 engages the fitting 42 and again makes the toggle. It will thus be seen that there is provided a positive drive from the main shaft of the sewing machine to effect the actuation of the pinking mechanism. Within this drive connection there is provided a mechanism or linkage, specifically the toggle, by means of which the pinking mechanism may be rendered inoperative at will.

The female knife 16 is supported on and secured to an overhanging plate 78. This plate is secured to the end portion 28c of the bracket 28 and extends towards the center of the machine. With this construction, the pinking attachment is complete in itself, the needle plate may be removed from the machine without disturbing the female knife, the relation of the pinking, i. e. the distance of the apex of the cut, to the needle may be varied by shifting the bracket 28 and by changing the length of the plate 78 and changing the male knife, the pinking may be effected nearer to or farther from the operator, that is adjusted in a direction parallel to the line of feed.

By the use of a folder, pinking may be effected concomitantly with top-stitching wherein one piece of cloth lies flat on the bed of the machine, overhanging the bed at the needle end, and the edge of the other is folded over so that the body of the cloth passes under the arm of the machine and over the pinking knives, the needle penetrating three layers of cloth and the stitching appearing on the top of the folded piece adjacent the fold. In this way the edges of the two pieces pass between the knives and top-stitching and pinking is effected simultaneously. If it is desired to utilize the sewing machine as a plain stitcher, it is only necessary to actuate the lever 51 to render the pinking mechanism inoperative. When the male knife is drawn within the female knife the bed of the machine is clear, a cover of the shape of the opening and having depending resilient detents may be inserted in the female knife and the machine may be used in the manner of an ordinary sewing machine. Likewise, it will be apparent that ordinary plain stitching and pinking may be performed simultaneously on the machine.

It will be obvious that various changes may be made by those skilled in the art in the details of the embodiment of the invention illustrated in the drawings and described above within the principle and scope of the invention as expressed in the appended claims.

I claim:

1. In a combined seaming and pinking mechanism, the combination comprising a frame, stitch-forming mechanism mounted in the frame, operating mechanism for the stitch-forming mechanism, pinking mechanism for serrating the edge of the material operated upon, and drive mechanism therefor including a positive track cam positively driven by said operating mechanism, a cam follower cooperating with the track cam and a positive drive connection between the cam follower and the pinking mechanism includ-

ing a longitudinally reciprocative connecting rod and flexible connections therewith.

2. In a combined seaming and pinking mechanism, the combination comprising a frame, 5 stitch-forming mechanism mounted in the frame, operating mechanism for the stitch-forming mechanism, pinking mechanism for serrating the edge of the material operated upon, and drive mechanism therefor including a positive track cam positively driven by said operating mechanism, a cam follower cooperating with the track cam and a positive drive connection between the cam follower and the pinking mechanism, includ- 10 ing a longitudinally reciprocative connecting rod and a pivotally connected linkage shiftable to render the pinking mechanism ineffective, and means for shifting said linkage.

3. In combination with a sewing machine having 15 stitch-forming mechanism, means for operating the stitch-forming mechanism and a work-supporting base, pinking mechanism including cooperating pinking knives, one of which is substantially vertically reciprocative, an oscillatory lever pivoted between its ends below said work-supporting base, a knife carrier pivotally secured to one end of said lever and arranged to project the knife above said work-supporting base, a positive drive connection for effecting positive actuation of the lever in both directions of its oscillations between said operating means for the 20 stitch-forming mechanism and the other end of said pivoted lever including means for rendering said connection inoperative to effect movement of said pivoted lever.

35 4. In combination with a sewing machine having 25 stitch-forming mechanism, means for operating the stitch-forming mechanism and a work-supporting base, pinking mechanism including cooperating pinking knives, one of which is substantially vertically reciprocative, an oscillatory lever pivoted between its ends below said work-supporting base, a knife carrier pivotally secured to one end of said lever and arranged to project the knife above said work-supporting base, a positive drive connection for effecting positive 30 actuation of the lever in both directions of its oscillations between said operating means for the stitch-forming mechanism and the other end of said pivoted lever including means for rendering said connection inoperative to effect movement of said pivoted lever.

35 45 5. In combination with a sewing machine having 40 stitch-forming mechanism, means for operating the stitch-forming mechanism and a work-supporting base, pinking mechanism including cooperating pinking knives, one of which is substantially vertically reciprocative, an oscillatory lever pivoted between its ends below said work-supporting base, a knife carrier pivotally secured to one end of said lever and arranged to project the knife above said work-supporting base, a positive drive connection for effecting positive 45 actuation of the lever in both directions of its oscillations between said operating means for the stitch-forming mechanism and the other end of said pivoted lever including means for rendering said connection inoperative to effect movement of said pivoted lever, and manually operative 50 control means therefor.

55 60 6. In combination with a sewing machine having 55 stitch-forming mechanism, means for operating the stitch-forming mechanism and a work-supporting base, pinking mechanism including a female knife and a cooperating substantially vertically reciprocative male knife, an oscillatory lever pivotally mounted below said work-supporting base, a carrier for the male knife pivotally secured to one end of said lever and arranged to project the male knife through the female knife, a positive drive connection for effecting positive 65 actuation of the lever in both directions of its oscillations between said operating means for the stitch-forming mechanism and the other end of said pivoted lever including means for withdrawing the male knife within the female knife and rendering said drive connection inoperative to effect movement of said pivoted lever.

70 75 6. In combination with a sewing machine having 70 stitch-forming mechanism, means for operating the stitch-forming mechanism and a work-supporting base, pinking mechanism including a female knife having a V-shaped opening therein,

a cooperating substantially vertically reciprocative male knife arranged to coact with the female knife to effect a cut on the downward stroke, a lever pivoted between its ends below said work-supporting base, a knife carrier for said male knife pivotally secured to one end of said lever, a second lever pivoted coaxially with said first mentioned lever, toggle-jointed links connecting said levers, a positive drive connection between

said second mentioned lever and said operating means for the stitch-forming mechanism, and manually releasable means for holding said toggle-jointed links in substantial alignment for transmitting oscillating movement from said second mentioned lever to said first mentioned lever.

GEOFFREY STEVENSON.
